(57) **CLAIM**

The ornamental design for a video fader handle, as shown and described.

DESCRIPTION

FIG. 1 is a front perspective view of a video fader handle showing our new design;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a bottom view thereof.

The broken line showing of a fader system for the video fader handle is for the purpose of illustrating environmental structure and forms no part of the claimed design.
